FURNACE FRONT WALL CONSTRUCTION
FOR USE WITH SPREADER STOKERSEarle C. Miller, Worcester, Mass., assignor to
Riley Stoker Corporation, Worcester, Mass., a
corporation of Massachusetts

Application November 15, 1946, Serial No. 710,162.

12 Claims. (Cl. 110—1)

1

This invention relates to furnace wall constructions, and more particularly to walls for furnaces arranged to be fired by stokers of the well-known spreader type.

The usual spreader stoker furnace includes an upright metal front plate having an opening therein through which the fuel is projected rearwardly by the action of revolving rotor blades located in front of the opening. The fine particles of fuel burn in suspension, and the coarse particles are deposited upon a grate to form a fuel bed. In order to permit inspection of the fuel bed and the use of firing tools thereon when necessary, a fire door opening is provided in the front plate beneath the fuel admission opening. A dead plate is usually provided between the grate and the fire door opening.

In such a furnace it is important to protect the portion of the front plate between the two openings from the furnace heat and from the abrasive action of the entering fuel. It is also important to prevent fuel from being deposited in appreciable amounts on the dead plate. Furthermore, the rotor and particularly the shaft portion thereof should be shielded so far as possible from radiant heat. These facts have been recognized, and various structures have been mounted at the rear of the front plate, directly beneath the fuel admission opening, in attempts to solve the problem. However, these prior arrangements have been subject to difficulties in operation. Certain of these constructions have been incapable of withstanding the severe radiant heat to which they are necessarily subjected. Other constructions have been readily worn away by the action of the entering fuel, or readily damaged by accidental engagement of firing tools therewith, or easily cracked by the effect of cold air entering the furnace when the fire door is opened.

It is accordingly one object of the invention to provide an improved wall construction for use with spreader stokers, whereby the above-mentioned difficulties will be avoided.

It is a further object of the invention to provide a furnace wall construction including a metal front plate having a fuel admission opening, and parts secured to the rear of the front plate directly beneath the opening so constructed and arranged as to protect the front plate from the furnace heat and from abrasion by the entering fuel.

It is a further object of the invention to provide a furnace wall of simple and inexpensive construction, which will withstand severe operating conditions throughout a long life of useful

2

service, the various heat-exposed parts being arranged for easy replacement in a simple manner when required.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a vertical section through the front wall of a spreader stoker furnace, the section being taken on the line 1—1 of Fig. 2;

Fig. 2 is a section taken on the line 2—2 of Fig. 1;

Fig. 3 is a section taken on the line 3—3 of Fig. 1;

Fig. 4 is an enlarged view of a portion of Fig. 1;

Fig. 5 is a plan view showing the detailed construction of a support bracket;

Fig. 6 is a rear elevation of the support bracket;

Fig. 7 is a section taken on the line 7—7 of Fig. 6;

Fig. 8 is a perspective view of a refractory block;

Fig. 9 is a perspective view of a retainer block; and

Fig. 10 is a perspective view of a pipe support.

The embodiment illustrated comprises a spreader stoker furnace having a grate 15, dead plates 16 in front of the grate, and upright side walls 17 on opposite sides of the furnace. At the front of the dead plates there is provided an upright metal front plate 19 having two laterally spaced rectangular openings 20 therethrough immediately above the level of the grate and dead plates. These openings 20 are normally closed by fire doors 21 mounted on the front surface of the plate 19. The front plate 19 is also provided with two rectangular fuel admission openings 23 which are located a short distance above the respective fire door openings 20. The opposite sides of each opening 23 are protected by upright plates 24 of heat-resisting metal, and the upper edge of each opening is protected by a deflector plate 25 of similar material. Upright piers 27 of refractory material are supported on the dead plates 16 and extend upwardly at opposite sides of the openings 20 and 23. In front of each fuel admission opening 23 there is mounted a spreader stoker mechanism including a housing 29, a horizontal rotatable shaft 30 supported in the housing, and blades or paddles 31 mounted on the shaft. The housing 29 slightly overlaps the lower

edge of the opening 23 in the front plate and provides a narrow ledge 32 which extends horizontally across the full width of this opening. It will be understood that fuel, for example crushed coal, will be delivered to the revolving blades 31 in a well-known manner by a suitable feeding mechanism, and that the blades will throw the fuel rearwardly through the opening 23 for combustion partly in suspension and partly in a fuel bed on the grate 15.

The present invention provides a highly effective construction for protecting the portions of the front plate 19 beneath the fuel admission openings 23. For this purpose a horizontal bar 34 is mounted behind and close to the front plate at substantially the same height as the lower edges of the openings 23. This bar is supported by means of hangers 35 which are bolted to the front plate on opposite sides of the openings 23. Each hanger includes a hook 36 which extends rearwardly beneath the bar 34. These hangers are protected from the furnace heat by the intervening refractory material of the piers 27. The bar 34 is preferably made in the form of a pipe of circular cross section, through which cooling water is circulated from a suitable source, such as the city water supply.

This pipe 34 serves as a support for a row of retainer blocks 38 at each opening 23, these blocks extending between the side plates 24. As best shown in Fig. 9, each block 38 is provided with a transverse groove 39 of semi-circular cross section in its lower surface, and with a depending tongue or flange 40 immediately behind this groove. The lower front corner of each block is notched to provide a downwardly facing shoulder 42. The upper surface 43 of the front portion of each block is substantially horizontal, and the upper surface 44 of the rear portion of the block is inclined downwardly and rearwardly. The two opposite vertical side faces of the block are parallel. As shown in Fig. 4, when the parts are assembled the concave surface of the groove 39 will engage the pipe 34, and the shoulder 42 will rest upon the ledge 32 on the housing 29. The blocks 38 are preferably made of a heat-resisting metal, such as a suitable cast iron alloy.

Supporting members 46 are mounted on the rear surface of the front plate 19 immediately above the fire door openings 20 and somewhat below the pipe 34. These members are L-shaped in cross section, with an upwardly extending vertical flange 47 and a rearwardly extending horizontal flange 48 forming a shelf. The vertical flange 47 is provided with openings 50 to receive bolts 51 which fasten the member to the front plate. The horizontal flange 48 is provided on its upper surface and its rear edge with laterally spaced narrow ribs 53. Rows of openings 54 are provided through the flange 48 between the ribs 53 for the downward discharge of air, as will be explained hereinafter. The members 46 are rather short, and as shown in Figure 2 three of them are required to extend across each fire door opening 20. They are preferably made of a heat-resisting alloy similar to that used for the blocks 38.

The members 46 above each door opening 20 serve to support a row of blocks 56 which are preferably formed of a suitable refractory material, such as baked fire clay. As best shown in Figure 8, the upper surface 57 of each block 56 is inclined downwardly and rearwardly, and the upper and lower rear corners of the block are well rounded. The lower front corner of the block 75 to replace the refractory blocks 56, they may

is provided with a transverse notch 58. A hook-shaped portion 60 projects forwardly and upwardly from the front of the block to provide an upwardly-open transverse groove 61. The two opposite vertical side faces of the block are parallel. At assembly, as shown in Fig. 4, the blocks 56 will rest on the supporting members 46 in positions spaced rearwardly from the plate 19, with the rear portions of the horizontal flanges 48 engaging the notches 58, and the lower ends of the tongues 40 on the retainer blocks 38 engaging the notches 61 behind the hooked portions 60. Thus the tongues 40 interlock with the hooked portions 60 to prevent rearward movement of the refractory blocks 56. The upper surfaces 57 of the refractory blocks 56 lie in substantially the same plane as the upper surfaces 44 of the retainer blocks 38. Preferably, a sheet 63 of asbestos or other heat insulating material is inserted between the front surfaces of the refractory blocks and the adjacent rear surfaces of the tongues 40.

The blocks 38 and 56, the front plate 19, and the members 46 enclose a transversely extending chamber 65 above each of the fire door openings 20. These chambers 65 are supplied with air, and for this purpose vertical ducts 66-67 are provided at the sides of the openings 20 to connect the ends of the chambers with the space beneath the grate 15 and the dead plates 16. These ducts are located between the front plate 19 and the refractory piers 27, so that the piers shield the ducts from the furnace heat.

The operation of the invention will now be apparent from the above disclosure. The revolving blades 31 will throw fuel rearwardly through the openings 23 to form a bed of burning fuel on the grate 15, and air for combustion will enter the space beneath the grate either by the natural draft of the furnace or preferably from a suitable forced draft fan in known manner. The blocks 38 and 56 will prevent the fuel from being deposited in any appreciable quantities on the dead plates 16. Fuel particles which slide rearwardly along the upper surface of these blocks and drop over the rear edges of the blocks 56 will be picked up by the air stream which flows rearwardly beneath the blocks 56 from the openings 54 in the members 46. Air reaches these openings after flowing upwardly through the ducts 66-67 and thence along the chambers 65 in cooling relation to the various parts forming the walls thereof. The blocks 38, which are effectively cooled by their contact with the water pipe 38, protect the front plate 19 and the blocks 56 from the abrasive action of the rearwardly traveling fuel particles and shield the rotor 30-31 from the radiant heat of the furnace. Fire tools may be inserted through the fire door openings 20 for the purpose of working upon the fuel bed when required, and the metal parts 46 will shield the refractory blocks 56 from damage through accidental contact with such tools. The stream of comparatively hot air issuing from the openings 54 will flow rearwardly beneath the blocks 56 and protect them against the chilling effect of cold air entering through the openings 20 when the doors 21 are opened, such chilling being particularly harmful to hot refractory material. The ribs 53 serve to reduce the transfer of heat from the blocks 56 to the metal parts 46, and the sheet 63 of insulating material serves to reduce the transfer of heat from the blocks 56 to the metal blocks 38. If it ever becomes necessary

easily be released for rearward withdrawal by lifting the blocks 38 from the pipe 35.

Having thus described my invention, what I claim as new and desire to secure by Letters Patent is:

1. A wall for a spreader stoker furnace comprising an upright front plate having an opening for the admission of fuel to the furnace in a rearward direction, a shelf behind the plate and spaced below the opening, a block of refractory material supported on the shelf, a horizontal bar behind the plate near the lower edge of the opening, and a retainer block supported on the bar, the retainer block and the refractory block having portions which interlock to prevent rearward movement of the refractory block.

2. A wall for a spreader stoker furnace comprising an upright front plate having an opening for the admission of fuel to the furnace in a rearward direction, a shelf behind the plate and spaced below the opening, a block of refractory material supported on the shelf, a horizontal water-cooled pipe behind the plate near the lower edge of the opening, and a retainer block supported on the pipe and having a groove in its lower surface to receive the pipe, the retainer block and the refractory block having portions which interlock to prevent rearward movement of the refractory block.

3. A wall for a spreader stoker furnace comprising an upright front plate having an opening for the admission of fuel to the furnace in a rearward direction, a shelf behind the plate and spaced below the opening, a block of refractory material supported on the shelf and having an upwardly-open transverse groove, a horizontal bar behind the plate near the lower edge of the opening, and a retainer block supported on the bar and having a groove in its lower surface to receive the bar, the rear portion of the retainer block extending downwardly into the transverse groove in the refractory block to prevent rearward movement of the retainer block.

4. A wall for a spreader stoker furnace comprising an upright front plate having an opening for the admission of fuel to the furnace in a rearward direction, a shelf behind the plate and spaced below the opening, a block of refractory material supported on the shelf and having an upwardly projecting hook-shaped portion, a horizontal water-cooled pipe behind the plate near the lower edge of the opening, and a retainer block supported on the pipe and having a groove in its lower surface to receive the pipe, the retainer block including a tongue which extends downwardly behind the pipe and into engagement with the said hook-shaped portion to prevent rearward movement of the refractory block.

5. A wall for a spreader stoker furnace comprising an upright front plate having an opening for the admission of fuel to the furnace in a rearward direction, a shelf behind the plate and spaced below the opening, a block of refractory material supported on the shelf and having an upwardly projecting hook-shaped portion, the upper surface of the block being inclined downwardly and rearwardly, a horizontal water-cooled pipe behind the plate near the lower edge of the opening, and a retainer block supported on the pipe and having a groove in its lower surface to receive the pipe, the retainer block including a tongue which extends downwardly behind the pipe and into engagement with the said hook-shaped portion to prevent rearward movement of the refractory block, the retainer block

having a downwardly and rearwardly inclined upper surface in substantially the same plane as the upper surface of the refractory block.

6. A wall for a spreader stoker furnace comprising an upright front plate having an opening for the admission of fuel to the furnace in a rearward direction, a shelf behind the plate and spaced below the opening, a block of refractory material supported on the shelf and having an upwardly projecting hook-shaped portion, a horizontal water-cooled pipe behind the plate near the lower edge of the opening, and a retainer block supported on the pipe and having a groove in its lower surface to receive the pipe, the retainer block including a tongue which extends downwardly behind the pipe and into engagement with the said hook-shaped portion to prevent rearward movement of the refractory block, the front portion of the retainer block being located within the fuel admission opening in position to protect the lower edge thereof from radiant heat and from abrasion by the entering fuel.

7. A wall for a spreader stoker furnace comprising an upright front plate having an opening for the admission of fuel to the furnace in a rearward direction, a shelf behind the plate and spaced below the opening, a block of refractory material supported on the shelf and having an upwardly projecting hook-shaped portion, a horizontal water-cooled pipe behind the plate near the lower edge of the opening, a retainer block supported on the pipe and having a groove in its lower surface to receive the pipe, the retainer block including a tongue which extends downwardly behind the pipe and into engagement with the said hook-shaped portion to prevent rearward movement of the refractory block, and heat insulating material between the rear surface of the retainer block and the adjacent front surface of the refractory block.

8. A wall for a spreader stoker furnace comprising an upright front plate having an opening for the admission of fuel to the furnace in a rearward direction, a shelf behind the plate and spaced below the opening, a block of refractory material supported on the shelf and having an upwardly projecting hook-shaped portion, the refractory block having a notch in its lower front portion into which the shelf extends, a horizontal water-cooled pipe behind the plate near the lower edge of the opening, and a retainer block supported on the pipe and having a groove in its lower surface to receive the pipe, the retainer block including a tongue which extends downwardly behind the pipe and into engagement with the said hook-shaped portion to prevent rearward movement of the refractory block.

9. A wall for a spreader stoker furnace comprising an upright front plate having an opening for the admission of fuel to the furnace in a rearward direction and a fire door opening spaced below the fuel admission opening, a horizontal member of L-shape in cross section located behind the plate above the fire door opening and spaced below the fuel admission opening, the said member including an upwardly extending vertical flange secured to the plate and a rearwardly extending horizontal flange forming a shelf, a row of refractory blocks supported on the shelf and shaped to provide upwardly projecting hook-shaped portions, a horizontal water-cooled pipe behind the plate near the lower edge of the fuel admission opening, and a row of retainer blocks supported on the pipe and each having a groove in its lower surface to receive the pipe, the re-

tainer blocks having tongues which extend downwardly behind the pipe and into engagement with the said hook-shaped portions to prevent rearward movement of the refractory blocks.

10. A wall for a spreader stoker furnace comprising an upright front plate having an opening for the admission of fuel to the furnace in a rearward direction and a fire door opening spaced below the fuel admission opening, a shelf behind the plate above the fire door opening and spaced below the fuel admission opening, a row of refractory blocks supported on the shelf and spaced rearwardly from the plate to provide a chamber, a horizontal bar behind the plate near the lower edge of the fuel-admission opening, a row of retainer blocks supported on the bar, the retainer blocks and the refractory blocks having portions which interlock to prevent rearward movement of the refractory blocks, and upright ducts behind the plate on opposite sides of the fire door opening arranged to supply air to the ends of the chamber, the shelf having openings therein through which the air is discharged downwardly from the chamber.

11. A wall for a spreader stoker furnace comprising an upright front plate having an opening for the admission of fuel to the furnace in a rearward direction and a fire door opening spaced below the fuel admission opening, a shelf behind the plate above the fire door opening and spaced below the fuel admission opening, a row of refractory blocks supported on the shelf and spaced rearwardly from the plate to provide a chamber, a horizontal bar behind the plate near the lower edge of the fuel-admission opening, a row of retainer blocks supported on the bar, the retainer blocks and the refractory blocks having portions which interlock to prevent rearward movement of the refractory blocks, upright ducts behind the plate on opposite sides of the fire door opening arranged to supply air to the ends of the chamber, the shelf having openings therein through which the air is discharged downwardly from the chamber, and upright piers of refractory material

directly behind the ducts to protect them from the radiant heat of the furnace.

12. A wall for a spreader stoker furnace comprising an upright front plate having an opening for the admission of fuel to the furnace in a rearward direction and a fire door opening spaced below the fuel admission opening, a shelf behind the plate above the fire door opening and spaced below the fuel admission opening, a row of refractory blocks supported on the shelf and spaced rearwardly from the plate to provide a chamber, the refractory blocks having upwardly projecting hook-shaped portions, a horizontal water-cooled pipe behind the plate near the lower edge of the fuel admission opening, supporting means for the pipe secured to the rear surface of the plate, a row of retainer blocks supported on the pipe and each having a groove in its lower surface to receive the pipe, the retainer blocks having tongues which extend downwardly behind the pipe and into engagement with the said hook-shaped portions to prevent rearward movement of the refractory blocks, the front portions of the retainer blocks being located within the fuel admission opening in position to protect the lower edge thereof from radiant heat and from abrasion by the entering fuel, and upright ducts behind the plate on opposite sides of the fire door opening arranged to supply air to the ends of the chambers, the shelf having openings therein through which the air is discharged downwardly from the chamber.
